Primary Examiner — Mark A Goodwin*Assistant Examiner* — William B Melliar(74) *Attorney, Agent, or Firm* — Breiner & Breiner, L.L.C.(57) **CLAIM**

The ornamental design for a PORTABLE LIGHT as shown and described.

DESCRIPTION

FIG. 1 is a front/side elevational perspective view of the portable light;

FIG. 2 is a top view of the portable light;

FIG. 3 is a first side view of the portable light;

FIG. 4 is a second side view of the portable light;

FIG. 5 is a bottom view of the portable light;

FIG. 6 is a first end view of the portable light;

FIG. 7 is a second end view of the portable light; and

FIG. 8 is a view of the portable light in an environment of use;

The broken lines in the figures represent portions of the portable light that form no part of the claimed design. The additional broken lines shown in FIG. 8 depict environment only and form no part thereof.
